GANG-TYPE CLOSURE FOR STORAGE BATTERIES

William W. Guild, 4726 Stanley, Warren, Mich.

Filed Feb. 14, 1963, Ser. No. 73,566

Term of patent 14 years

(Cl. D26—6)

FIG. 1 is a top plan view of a gang-type closure for storage batteries, showing my new design;

FIG. 2 is a side elevational view thereof;

FIG. 3 is a fragmentary bottom plan view thereof, a portion being omitted for convenience in illustration.

The side not shown is the same as the side shown.

I claim:

The ornamental design for a gang-type closure for storage batteries, as shown and described.
